US00D786087S

(12) **United States Design Patent** (10) Patent No.: **US D786,087 S**
 McCoy et al. (45) Date of Patent: ** May 9, 2017

(54) **BOTTLE**(71) Applicant: **CVS Pharmacy, Inc.**, Woonsocket, RI (US)(72) Inventors: **Ryan P. McCoy**, Falcon Heights, MN (US); **Stacy Abel**, Maple Grove, MN (US); **Matthew P. Franks**, Austin, MN (US); **Adam D. Hoppus**, Minneapolis, MN (US); **Duane Sawyer**, York, PA (US); **Gordon Beecroft**, Leola, PA (US); **John Vassallo**, Lititz, PA (US); **Michael Makhlof**, Lititz, PA (US)(73) Assignee: **CVS Pharmacy, Inc.**, Woonsocket, RI (US)(**) Term: **15 Years**(21) Appl. No.: **29/531,277**(22) Filed: **Jun. 24, 2015****Related U.S. Application Data**

(63) Continuation of application No. 14/524,910, filed on Oct. 27, 2014, now Pat. No. 9,085,396, which is a continuation of application No. 13/281,338, filed on Oct. 25, 2011, now Pat. No. 8,870,004.

(51) LOC (10) Cl. **09-01**

(52) U.S. Cl.

(57) **CLAIM**

The ornamental design for a bottle, as shown and described.

DESCRIPTION

FIG. 1 is a top, front, perspective view of a bottle showing a first embodiment of our new design;

FIG. 2 is a bottom, rear, perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and

FIG. 8 is a bottom view thereof.

FIG. 9 is a top, front, perspective view of a bottle showing a second embodiment of our new design;

FIG. 10 is a bottom, rear, perspective view thereof;

FIG. 11 is a front view thereof;

FIG. 12 is a rear view thereof;

FIG. 13 is a right side view thereof;

FIG. 14 is a left side view thereof;

FIG. 15 is a top view thereof; and

FIG. 16 is a bottom view thereof.

FIG. 17 is a top, front, perspective view of a bottle showing a third embodiment of our new design;

FIG. 18 is a bottom, rear, perspective view thereof;

FIG. 19 is a front view thereof;

FIG. 20 is a rear view thereof;

FIG. 21 is a right side view thereof;

FIG. 22 is a left side view thereof;

FIG. 23 is a top view thereof; and

FIG. 24 is a bottom view thereof.

The evenly spaced dash-dash broken lines in the drawings illustrate the portions of the bottle that form no part of the claimed design.
